UNITED STATES PATENT OFFICE

GRAY WASHINGTON JOHNSTON, OF NEW YORK, N. Y.

MECHANICAL MOVEMENT.

No. 809,693.

Specification of Letters Patent.

Patented Jan. 9, 1906.

Application filed March 27, 1905. Serial No. 252,244.

To all whom it may concern:

Be it known that I, GRAY WASHINGTON JOHNSTON, a citizen of the United States, residing at the city of New York, in the borough 5 of Manhattan and State of New York, have invented certain new and useful Improvements in Mechanical Movements, of which the following is a full, clear, and exact description.

My invention relates to mechanical movements, the object of the same being to provide novel means for effecting the lateral movement of one part alternately in opposite directions from successive movements of another part in the same direction.

15 The invention consists of a reciprocable driving member, a driven member capable of lateral movement, the latter having a substantially V-shaped slot therein, and a pivotally-mounted connecting-piece between the driving and driven members, the said connecting-piece having a projection thereon which is movable in said slot.

The invention also consists of certain features and details of construction and combinations of parts, which will be hereinafter more fully described and claimed.

In the drawings forming part of this specification, Figure 1 is an elevation of the device, showing the driving member in its extended 30 position and the driven member at the limit of its movement in one direction, the parts being ready for operation. Fig. 2 is a similar view showing the positions the parts assume when the driving member is retracted. Fig. 3 is a view similar to Fig. 1, showing the next position the parts assume, and Fig. 4 is an elevation showing the driven member at a point midway between the opposite ends of its stroke.

40 The driving member 1 has been shown as the core of a solenoid 2, mounted upon a back plate or support 3. The solenoid acts as a guide for the driving member 1, serving to constrain the movement thereof in a right line. Said driving member may, however, be any other part capable of reciprocating movement. The core 1 and the solenoid 2 have been shown as vertically disposed, so that when said solenoid is deenergized the core 1 45 will fall by gravity. This, however, is not essential, as these parts may be horizontally or otherwise disposed so long as means are provided for returning the driving member or core 1 to its normal outermost position. 55 The driven member 4 has been shown in the form of a rectangular plate. It is not neces-

sary, however, that this part be a plate or that it assume the particular shape described. It is pivoted at 5 to the back plate or support 3 and is provided with a substantially V-shaped slot 6. By reason of the pivotal connection of the member 4 with the back plate 3 the same is capable of lateral swinging movements in opposite directions. The slot 6 has been shown as having the branches 7 and 8 thereof extending upwardly and outwardly from their meeting point, and the pivot 5 is located at a central point between said branches. Said pivot is also located at a point in line with the direction of movement of the driving member or core 1. The side walls of the branches 7 and 8 of the slot 6 are preferably rectilinear. They may, however, be curved or otherwise shaped without departing from the invention. The apex 9, formed at the intersection of the upper or inner walls of the branches 7 and 8 of said slot, is in line with the pivot 5 and the direction of movement of the core 1 when the driven member 4 is at a point midway between the opposite ends of its strokes, as clearly shown in Fig. 4 of the drawings. Opposite the apex 9 the slot 6 is enlarged or rounded, as shown at 10, forming pockets or recesses 11 and 12 between said rounded portion and the branches 7 and 8 of the slot and on opposite sides of said apex. Coöperating with these parts is a link or connecting-piece 13, the same being pivoted at 14 to the driving member 1 and having a pin or projection 15 thereon which fits and moves within the slot 6. 90

In order that the driven member 4 may be frictionally held at the limit of its movement in each direction, I have shown an arm 16, connected to said driven member, which is adapted to be engaged by the clips 17. Any other means, however, for holding the driven member 4 against movement may be substituted for that shown.

Assuming the parts to be in the positions in which they are shown in Fig. 1 of the drawings with the core 1 in extended position and the pin or projection 15 seated in the pocket 12, the operation is as follows: The solenoid 2 is energized by causing a flow of electric current therethrough, and when this is done the core or driving member 1 will be raised or retracted. The upward movement of this core or driving member 1 raises the link 13 and causes the pin or projection 15 thereon to ride along the inclined wall of the left-hand branch 8 of the slot 6. This latter action causes the lateral swinging movement of the

driven member 4 on its pivot 5 from right to left, this swinging movement being continued until the driven member 2 reaches the end of its stroke, as shown in Fig. 2, where it is frictionally held by the engagement of the arm 16 with the clip 17. When the solenoid 2 is deenergized, the core or driving member 1 and the link 13 will return to their lowermost or outermost positions. In so doing the pin 10 or projection 15 on the link 13 will ride along the lower wall of the left-hand branch 8 of the slot 6 until it reaches the enlarged portion 10 of said slot and seats itself in the pocket 11 at the right-hand end of said enlarged portion, as shown in Fig. 3. When in this position, it will be seen that said pin or projection lies to the right of the apex 9 of the slot 6. Consequently upon the next upward or inward movement of the core or driving member 1 20 said pin or projection 15 will ride along the inclined upper wall of the right-hand branch 7 of the slot 6, causing the swinging movement of the driven member 4 on its pivot 5 from left to right. When the solenoid 2 is again deenergized, the core 1 and link 13 will 25 return to their lowermost or outermost positions, and the pin or projection 15 will finally come to rest in the pocket 12 at the left-hand end of the enlarged portion 10 of the slot 6 to the left of the apex 9, as shown in Fig. 1. It will thus be seen that upon successive reciprocations of the driving member 1 in the same direction the driven member 4 will be laterally moved alternately in opposite directions.

30 This movement may be utilized for many different purposes—for example, the driven member 4 may carry or be connected with the movable part of an electric switch or may be connected with the switch-point of a railway 35 for the operation of the same alternately in opposite directions.

Having now described my invention, what I claim is—

1. The combination with a solenoid of a reciprocable driving member operated by said solenoid, a pivotally-mounted driven member capable of swinging movement transversely of said driving member, the pivot of the driven member being in line with the direction of movement of said driving member and said driving member being constrained to move in the line of said pivot, and the driven member being provided with angularly-arranged walls diverging from the apex formed at their meeting-point, to opposite sides of said pivot, and a connecting element pivoted to said driving member and dependent therefrom and carrying a projection adapted to ride upon and engage said walls, alternately, being shifted 40 from one to the other by gravity together with the camming action of said walls upon successive movements of the driving member in the same direction.
2. The combination with a reciprocable

driving member, of a pivotally-mounted driven member capable of swinging movement transversely of said driving member, the line of reciprocation of said driving member always containing the pivot of the driven member, the said driven member being provided with a substantially V-shaped slot whose branches diverge to points on opposite sides of the pivot and whose central portion is enlarged, forming pockets on opposite sides of the apex formed at the intersection of the upper or inner walls of said branches, a connecting element pivoted to said driving member and carrying a projection which is movable in said slot, which seats itself in one or the other of said pockets by virtue of gravity and the camming action of said slot when said driving member is in retracted position, and which engages the walls of said slot, alternately, upon successive movements of said driving member in the same direction, and frictional means for retaining said driven member at the limit of its movement in each direction, whereby the driven member is moved in alternate directions upon each reciprocation of the driving member.

3. In a device of the class described, a support or frame, a solenoid disposed upon said frame, contacts also mounted on said frame, a member pivoted upon said frame to swing into engagement with said contacts alternately and having cam-surfaces thereupon, a core slidably mounted in said solenoid, a link pivoted to said core and having a part engaging said cam-surfaces, frictional means for holding the pivoted member in either of its extreme positions, whereby said pivoted link is cammed into engagement with alternate cam-surfaces upon the pivoted member at successive actuations of the core of the solenoid.

4. The combination of a reciprocating driving member, a guide therefor arranged to constrain the movement of said reciprocating member in a right line, a pivotally-mounted driven member capable of swinging movement transversely of said driving member, the pivot of the driven member being in line with the direction of movement of said driving member, and the driven member being provided with angularly-arranged walls diverging from the apex formed at their meeting-point, to opposite sides of said pivot, and a connecting element pivoted to said driving member and carrying a projection adapted to engage said walls, alternately, upon successive movements of the driving member in the same direction.

In witness whereof I subscribe my signature in the presence of two witnesses.
